SLIPPER OR THE LIKE

Nathaniel B. Golovin, New York, N. Y.

Application September 6, 1951, Serial No. 16,536

Term of patent 3½ years

(Cl. D7—7)

To all whom it may concern:

Be it known that I, Nathaniel B. Golovin, a citizen of the United States of America, residing in New York city, county of New York, and State of New York, have invented a new, original, and ornamental Design for a Slipper or the like, of which the following is a specification, reference being had to the accompanying drawing, forming part thereof.

The figure is a side perspective view of a slipper or the like, showing my new design, the essential features being the upturned toe and the high part of the upper in the back, in combination with the braided element around the opening, all as illustrated on the drawing.

The opposite side presents substantially the same appearance, as shown.

I claim:

The ornamental design for a slipper or the like, substantially as shown and described.

NATHANIEL B. GOLOVIN.
